WRAPPING MACHINE

Isidore Dorman, Whitestone, N.Y. (112-19 14th Road, College Point, N.Y.), and Curtis G. Hoos, 144-06 37th Ave., Flushing, N.Y.

Filed Apr. 7, 1958, Ser. No. 726,875

12 Claims. (Cl. 53-194)

This invention relates to wrapping machines. More 15 specifically, it pertains to a machine for wrapping small articles, such as suppositories, candies or the like, in foil or similar material.

Heretofore, small articles such as suppositories, candies and the like had to be wrapped by hand or by cumbersome complicated machinery, both of which methods substantially increased the cost of the final product. Hand wrapping entailed increased labor costs and presented problems of sanitation, while the wrapping machinery previously used required relatively great amounts of floor space, was expensive, complicated to operate and in many instances did not produce the desired results.

It is therefore an object of this invention to provide a compact, unitary, fully automatic machine for wrapping small articles in foil or similar material.

It is also an object of the invention to provide a wrapping machine wherein individual wrapping containers are continuously formed from a source of wrapping material and may be thereafter filled, sealed and removed from the machine without requiring the constant attention of an operator.

It is another object of the invention to provide a wrapping machine wherein a strip of wrapping material, emanating from a source of supply, is folded into a tube, cut to a desired length, closed at one end to form an open ended container and thereafter filled with a desired article of manufacture, closed at its open end and ejected from the machine, all steps following consecutively without requiring the attention of an operator.

It is a further object of the invention to provide a wrapping machine wherein a strip of wrapping material, emanating from a source of supply, is continuously fed to a mandrel, which cooperates with an open ended die to form open ended containers which thereafter may be automatically filled with an article of manufacture, sealed at their open end and ejected from the machine, all steps following consecutively without requiring the attention of an operator.

With these and other objects in mind, reference is had to the attached sheets of drawings, illustrating one form of the invention, wherein like characters represent like parts, and in which:

Figure 1 is a plan view of the wrapping machine of this invention;

Fig. 2 is a fragmentary side elevational view illustrating the various phases of operation of the machine in solid and dotted lines;

Fig. 3 is a fragmentary view, partially in section, taken in the direction of the arrows 3-3 in Fig. 1;

Fig. 4 is a fragmentary sectional view illustrating the step of folding a continuously supplied ribbon of wrapping material into a tube;

Fig. 5 is a fragmentary sectional view illustrating the step of cutting the folded wrapping material into tubes of a desired length;

Fig. 6 is a cross-sectional view taken in the direction of the arrows 6-6 in Fig. 5;

2

Fig. 7 is a fragmentary sectional view illustrating the step of closing one end of the wrapping material tube to form an open ended container;

Fig. 8 is a fragmentary sectional view illustrating the step of inserting the article to be wrapped into the open ended container;

Fig. 9 is a fragmentary sectional view illustrating the filled open ended container positioned preparatory to having its open end closed;

Fig. 10 is a view taken in the direction of the arrows 10-10 in Fig. 9;

Fig. 11 is a fragmentary sectional view illustrating the step of closing the open end of the article filled open ended container;

Fig. 12 is a view, partially broken away and in section, of the wrapped article; and

Fig. 13 is an end view of the wrapped article of Fig. 12, taken in the direction of the arrows 13-13.

Referring now to the drawings, and Figs. 1 to 3 in particular, a base 20 mounts a motor 21 and a speed reducer 22 which are connected, in driving relation, through a chain belt 23, to an operating assembly, generally indicated by the numeral 24. A drive shaft 25, connected through a pulley 26 to the belt 23, is journaled in posts 27, 28, and 29, mounted on base 20, and carries a plurality of operating cams, to be more fully described below, for rotation therewith. Also mounted on shaft 25, for rotation therewith, is a rubber covered roller 30, which drives a second rubber covered roller 31, journaled in posts 28 and 29, the pair of rollers cooperating to continuously feed a ribbon 32, of foil or similar wrapping material, from a source of supply (not shown).

Spaced from shaft 25, and in line with the path of feed of wrapping material ribbon 32, are supports 33, which are mounted on the base and adapted to movably support a spring-back weight 34. The spring-back weight, which includes a pair of rollers 35 secured to a shaft 36, is adapted to ride above and in engagement with ribbon 32, for a purpose to be discussed below.

Continuing along the path of feed of ribbon 32, a folder or trumpet die 37, mounted on base 20, turns the longitudinal edges of the ribbon upwardly to form a tube and guides the same around a mandrel 38. The mandrel, which extends parallel with frame 20 in the direction of feed of the ribbon 32, is connected by a support 39 to a frame 40, which, in turn, is slidably mounted by the base 20 (Fig. 3). A vacuum is adapted to be drawn on the mandrel, through support 39 and the vacuum channel 41, formed in the frame 40, when the frame is in alignment with vacuum coupling 42, from a source of vacuum (not shown). A sleeve 43, which is connected to said source of vacuum, through coupling 44 and passage 44a, is adapted to movably ensleeve mandrel 38, for forming the end of ribbon 32 into a tube 32a. Adjacent sleeve 43, and adapted to receive mandrel 38 with tube 32a, of wrapping material, ensleeved thereon, is an open ended forming die 45, which cooperates with the mandrel to close one end of the tube to form an open ended container 32b. The die 45, which is formed with

50 a passage 46 extending into the mandrel receiving chamber 47, for connecting the chamber to a source of air under pressure (not shown), is mounted for relative movement with respect to base 20. A chamber 46a is formed in the die to connect the same to a source of vacuum. 55 The die may, as shown in dotted lines in Fig. 2, be moved from its starting position, adjacent sleeve 43, to a station 48 for receiving an article of manufacture, such as a suppository, in container 32b, and thereafter to another station 49, at which point the open end of the container is closed and the wrapped article ejected from the die.

In the operation of the wrapping machine, the ribbon

32, which is fed from a roll or similar source of supply, extends between the rubber covered rollers 30, 31, which continuously feed a certain length of the ribbon on each revolution of the rollers, beneath spring-back weight 34, through folder or trumpet die 37 into sleeve 43. We have found it advantageous to continuously feed wrapping material from massive rolls, as accomplished by the rubber covered rollers, since intermittently pulling the ribbon from the roll would result in excessive breakage. The mandrel 38 moves to the position in sleeve 43, shown in Fig. 4, through the foil 32, which is held stationary on the inner surface of the sleeve by a vacuum being drawn through coupling 44 and passage 44a. The coupling is connected, through a valve 50, operated by follower 51 and cam 52, to said source of vacuum. As a result of the ribbon being held stationary in sleeve 43, the continuous feed of rollers 30, 31 causes a loop of ribbon to appear, as indicated at 56, for a purpose to be discussed below. With mandrel 38 in the above described position, and on the continued rotation of cam 52, by shaft 25, the valve 50 is shifted to disconnect the sleeve 43 from the source of vacuum and connect the mandrel thereto, through coupling 42, channel 41 and support 39. The shifting of the vacuum from the sleeve to the mandrel transfers the ribbon 32, of foil or similar material, from the inner surface of the sleeve to the outer surface of the mandrel. This transfer literally takes place with a snap and results in the ribbon smoothly adhering to the mandrel.

The mandrel 38 is moved to the right, as seen in Fig. 2, by cam 53, through follower 54 and linkage 55, such movement carrying the ribbon 32 through folder 37. The mandrel is adapted to move faster than the rollers 30, 31 can feed the ribbon to it, thereby eliminating the slack loop 56, when the mandrel reaches the position shown in Fig. 5. On eliminating the slack loop, the spring-back weight 34 is raised, by the ribbon, as indicated in dotted lines in Fig. 2, and the ribbon becomes taut as illustrated at 57.

It is here noted, that though the construction of the vacuum seizing portion of the sleeve and mandrel may be of many different types, in the illustrated form of the invention a series of adjacent parallel grooves 58 are provided, which are connected to the source of vacuum. The ribbon 32 rests on the lands 59, formed between the grooves. When a vacuum is drawn on the ribbon by the sleeve or the mandrel, the ribbon has a tendency to enter the grooves 58, thereby substantially locking it in position. In order to eliminate wrinkling of the ribbon as it is adhered to the mandrel, the openings 60 that connect the grooves with the central vacuum conduit 61 of the mandrel are positioned in a straight axial line, on a side of the mandrel opposed to the overlapped flap 62 of the ribbon, as shown in Fig. 6. Other means may, of course, be resorted to for preventing wrinkling of the ribbon 32.

Continued movement of mandrel 38 to the right, after ribbon 32 has become taut, as above described, results in slippage of the ribbon over the surface of the mandrel due to the restraining action of the rubber covered rollers 30, 31. Simultaneously, the shearing edge 63 of the mandrel enters the shearing collar 64 of the sleeve (Fig. 5) and, there being no clearance between edge 63 and collar 64, the ribbon 32, is parted at the line of contact, to form a substantially cylindrical tube 32a, adapted to move with the mandrel.

Shearing of the ribbon occurs once for each complete revolution of rollers 30, 31 and, since the ribbon is taut between the rollers and the plane of shear, an exact length of tubing is cut. At the instant of parting, the spring-back weight 34, which retains the ribbon 32 under tension, drops to the position indicated in solid lines in Fig. 2 and the ribbon springs back away from the collar 64 as indicated in Fig. 7. The spring-back action of the weight 34, on the ribbon 32 is necessary to facilitate the subsequent re-entry of the shearing edge 63 of the mandrel into the sleeve 43. If the ribbon is not drawn away from

the shearing collar and its leading edge is permitted to remain at the plane of shear it will be picked up by the retracting mandrel and mauled with the result that further operation will be substantially impossible.

5 During most of the travel of mandrel 38 to the right, the rounded forming end 65 thereof has been moving into the open ended forming die 45 as illustrated in Fig. 5. On the final movement of the mandrel to the right, the ribbon tube 32a, which overhangs the end of the mandrel 10 by slightly more than one half of its diameter (Fig. 5), encounters the shaped end wall 66 of the forming die, where with further movement of the mandrel, it is formed into a cylindrical container 32b having one end closed (Fig. 7).

15 During the movement of mandrel 38 to the right, as above described, vacuum control cam 52 has maintained vacuum control valve 50 in position to connect the mandrel and disconnect the sleeve from the source of vacuum. It at this point should be noted, that the forming die 45 is 20 connected to the source of vacuum through passage 46a, coupling 46b and the same conduits as sleeve 43 and therefore is simultaneously connected and disconnected with the sleeve. After container 32b has been formed in die 45, cam 52 shifts valve 50 to disconnect mandrel 38 25 from the source of vacuum and connect the sleeve and forming die thereto. As a result of this shift, the container 32b is transferred from the outer surface of the mandrel to the inner surface of the die, permitting the mandrel to be withdrawn to the left. Simultaneously, 30 the strip of foil 32 is transferred from the outer surface of the rear end of the mandrel to the inner surface of the sleeve enabling the forming end of the mandrel to be returned to its starting position within the sleeve as illustrated in Fig. 4. The forming die, which now has container 32b adhered to its inner surface may conveniently include a structure of grooves 58 and lands 59 as was described with respect to the mandrel and the sleeve.

35 When mandrel 38 has been moved to the left and comes to rest at its starting position, the forming die 45, with shaped container 32b mounted therein, is moved to station 48 adjacent the ejection point of a molding machine or a feeding device as indicated in dotted lines in Fig. 2 and illustrated in detail in Fig. 8. Movement of the forming die is controlled by cam 67 through follower 40 45 68 and linkage 69. It is contemplated that an article of manufacture such as a suppository, candy, lipstick or the like will be inserted in container 32b by means of plunger 70 or similar means. After the article has been seated in the container, the forming die 45 is moved, as a result of 45 the continued rotation of cam 67 to a position adjacent station 49 as indicated in dotted lines in Fig. 2 and illustrated in detail in Figs. 9 through 11.

50 Station 49, which is adapted to spin or wipe closed the open end of container 32b comprises a stationary member 71 secured to frame 20 of the machine and adapted to rotatably mount a cylindrical body 72. A bushing assembly 73 is mounted on cylindrical body 72, the assembly including a bearing collar 74 and a collar 75 keyed to the cylindrical body for rotation therewith. 55 A pulley 76 is keyed to cylindrical body 72 and connects the same in driving relation to motor 77 through belt 78. Mounted on body 72 between collar 75 and pulley 76 is a helical spring 79 adapted to retain the bushing assembly and pulley in spaced relationship with 60 respect to one another. A twister or wiper element 80 is pivotally secured at opposite sides of body 72 and is adapted to extend longitudinally of the same to a point outwardly of the end of the body adjacent forming die 45 between the former and pulley 76. The twister element 80 includes two substantially L-shaped arms, the short leg of each L-shaped arm terminating in a cam 81, and the arms being connected by a transverse container contact bar 82. A substantially U-shaped yoke 83 is pivotally connected to stationary member 71 as at 65 75 84 and slidably engages outwardly extending studs 85,

formed on bearing collar 74, in slots 86. In the operation of twister or closing station 49, the cylindrical body 72 is rotated by motor 77 and the yoke 83 which is connected through linkage 87 and follower 88 to cam 89 is pivoted in the direction of forming die 45, by the rotation of the cam, compressing spring 79 and forcing the thrust washer 90, on body 72, into engagement with rib 91 on stationary member 71. Continued pivoting of yoke 83 in the direction of the forming die further compresses the spring and shifts bushing 73 axially of the body to engage the camming portion 81 of twister element 80, thereby camming twister bar 82 into engagement with the open end of container 32b, mounted in the forming die (see dotted and solid lines in Fig. 11). In this manner, the open end of container 32b is closed providing a completely packaged article 92 as illustrated in Fig. 12.

It has been found, in addition to the fact that a very fine seal can be obtained by rotating a rounded blade transversely of the open end of a container, that there is a marked difference in the quality of the seal if the blade is turned into the overlapped flap of the container rather than in the direction of the overlap. If the blade or spinner is turned in the direction of the overlap the sealed end of the container is formed with a protruding ear of material but if it is rotated in the opposite direction a flat relatively smooth seal is provided as shown in detail at 92a in Figs. 12 and 13.

After container 32b has had its open end closed to form a finished packaged article 92, a cam 93, acting through a follower 94 opens a valve 95 to connect the passage 46, in the forming die 45, through coupling 96, to a source of air under pressure (not shown). The resulting air jet through coupling 96 and passage 46 ejects the packaged article 92 through the hollow chamber 97 which extends longitudinally of twister body 72 and thence through a tube 98 to any appropriate receptacle, not shown.

The invention, as above described, is adapted to be utilized in combination with a molding machine for articles such as suppositories, candy, lipstick and the like. Due to the multiplicity of functions performed by the machine, however, it is suitable for a wide variety of applications, the various elements of its structure being readily adapted to structural redesign facilitating its association with other machine and manufacturing systems. It is also contemplated that portions of the structure, and the principles on which they rely, may be utilized in an apparatus for the manufacture of article containers or wrappers.

Thus, among others, the several objects of the invention as aforesaid are achieved. Obviously, numerous changes in the structure may be resorted to without departing from the spirit of the invention as defined by the claims.

We claim:

1. An apparatus for wrapping articles comprising an open ended forming die; means for forming a tubular wrapper open at both ends, said tubular wrapper overhanging the leading end of said forming means, said means for forming said wrapper moving the wrapper into said die and cooperating therewith to fold the overhanging end of said wrapper and close the same to form an open ended container within said die; means for feeding an article to be wrapped into said open ended container while the same is positioned in said die; means for closing the open end of said container; and means for ejecting said container and article from said die.

2. An apparatus for wrapping articles comprising an open ended forming die; means for forming a tubular wrapping member; said means for forming said tubular wrapping member feeding said tubular wrapping member into said die, said forming means cooperating with said die to close an end of said member and form said member into an open ended container therein; means for inserting an article into said open ended container; means

for moving said die and inserting means relative to one another so that said article is inserted in said container; means for closing the open end of said container; means for moving said die and closing means relative to one another so that the open end of said container is closed; and means for ejecting said article and said container from said die.

3. An apparatus for wrapping articles comprising a frame, an open ended forming die mounted on said frame, a sleeve, means for feeding a ribbon of wrapping material into said sleeve, means for forming a tubular wrapping member in said sleeve, said means for forming said tubular wrapping member feeding said tubular wrapping member into said die and cooperating therewith for closing an end of said tube to form an open ended container, means for inserting an article into said open ended container, means for moving said die and inserting means relative to one another so that said article is inserted in said container, means for closing the open end of said container, means for moving said die and closing means relative to one another so that the open end of said container is closed and means for ejecting said article and said container from said die.

4. An apparatus for wrapping articles comprising an open ended forming die, a sleeve, means for feeding a ribbon of wrapping material into said sleeve for engagement with the inner surface thereof, a mandrel, means for moving said ribbon from said surface of said sleeve onto the outer surface of said mandrel for forming a tube thereon, means for cutting a desired length of tube for movement with said mandrel, means for moving said mandrel into said die and cooperating therewith to close an open end of said tube so that an open ended container is formed, means for inserting an article into said open ended container, means for moving said die and inserting means relative to one another so that said article is inserted in said container, means for closing the open end of said container, means for moving said die and closing means relative to one another so that the open end of said container is closed and means for ejecting said article and said container from said die.

5. An apparatus for wrapping articles comprising an open ended forming die, a sleeve, means for continuously feeding a ribbon of wrapping material into said sleeve, means for adhering said ribbon to the inner surface of said sleeve, a mandrel, means for adhering said ribbon to the outer surface of said mandrel and releasing the same from the inner surface of said sleeve for forming an elongated tube thereon, means for cutting a tube of desired length for movement with said mandrel, means for moving said mandrel and tube into said die, said mandrel cooperating with said die to close an open end of said tube and form an open ended container therein, means for inserting an article into said open ended container, means for moving said die and inserting means relative to one another so that said article is inserted in said container, means for closing the open end of said container, means for moving said die and closing means relative to one another so that the open end of said container is closed and means for ejecting said article and said container from said die.

6. An apparatus for wrapping articles comprising a frame, an open ended forming die mounted on said frame, a sleeve mounted on said frame adjacent said die, rollers mounted on said frame for continuously feeding a ribbon of wrapping material into said sleeve, means between said rollers and said sleeve for folding said ribbon to conform to the inner surface of said sleeve, means for adhering said ribbon to the inner surface of said sleeve, a mandrel mounted on said frame for longitudinal movement relative to said sleeve, means for transferring said ribbon from the sleeve to the outer surface of said mandrel, means for forming a tube of wrapping material of desired length on said mandrel for movement therewith, means for moving said mandrel and tube into said die,

said mandrel cooperating with said die to close an open end of said tube and form an open ended container therein, means for transferring said container from said mandrel to the inner surface of said die, means for inserting an article into said open ended container, means for moving said die and inserting means relative to one another so that said article is inserted in said container, means for closing the open end of said container, means for moving said die and closing means relative to one another so that the open end of said container is closed and means for ejecting said article and said container from said die.

7. An apparatus for wrapping articles comprising an open ended forming die, a sleeve, means for continuously feeding a ribbon of wrapping material into said sleeve, means for vacuum adhering said ribbon to the inner surface of said sleeve, a mandrel longitudinally movable through said sleeve, means for vacuum adhering said ribbon to said mandrel and releasing the same from said sleeve, said ribbon forming an elongated tube around said mandrel, means between said sleeve and said mandrel for cutting a tube of a desired length on said mandrel for movement therewith, means for drawing the uncut portion of said ribbon away from said cutting means and back into said sleeve, means for moving said mandrel and tube into said die, said mandrel cooperating with said die to close an open end of said tube and form an open ended container therein, means for vacuum adhering said container to the inner surface of said die and releasing the same from said mandrel, means for inserting an article into said open ended container, means for moving said die and inserting means relative to one another so that said article is inserted in said container, means for closing the open end of said container, means for moving said die and closing means relative to one another so that the open end of said container is closed and means for ejecting said article and said container from said die.

8. An apparatus for wrapping articles comprising an open ended forming die, a sleeve, means for continuously feeding a ribbon of wrapping material into said sleeve, a source of vacuum, means for connecting said sleeve to said source of vacuum so that said ribbon adheres to the inner surface of said sleeve, a mandrel longitudinally movable through said sleeve, means for connecting said mandrel to said source of vacuum and disconnecting said sleeve therefrom so that said ribbon adheres to said mandrel for movement outwardly of said sleeve, means forming part of said mandrel and sleeve cooperating to cut a length of said ribbon for movement with said mandrel, means forming part of said feeding means for drawing the uncut portion of said ribbon away from said cutting portion of said sleeve, means for moving said mandrel and the cut portion of said ribbon adhering thereto into said die, said mandrel cooperating with said die to form said cut portion of ribbon into an open ended container, means for connecting said die and said sleeve to said source of vacuum and disconnecting said mandrel therefrom so that said open ended container adheres to said die and the uncut portion of said ribbon adheres to said sleeve, means for withdrawing said mandrel from said die and back into said sleeve, means for inserting an article into said open ended container, means for moving said die and inserting means relative to one another so that said article is inserted in said container, means for closing the open end of said container, means for moving said die and closing means relative to one another so that the open end of said container is closed and means for ejecting said article and said container from said die.

9. An apparatus for wrapping articles comprising an open ended forming die, a sleeve, means for continuously feeding a ribbon of wrapping material into said sleeve, a source of vacuum, cam means for connecting said sleeve to said source of vacuum so that said ribbon adheres to the inner surface of said sleeve, a mandrel longitudinally

movable through said sleeve, cam means for connecting said mandrel to said source of vacuum and disconnecting said sleeve therefrom so that said ribbon adheres to said mandrel for movement outwardly of said sleeve, means forming part of said mandrel and sleeve cooperating to cut a length of said ribbon for continued movement with said mandrel, means for drawing the uncut portion of said ribbon away from said cutting portion of said sleeve, cam means for moving said mandrel and the cut portion of said ribbon into said die, said mandrel cooperating with said die to form said cut portion of ribbon into an open ended container, cam means for connecting said die and said sleeve to said source of vacuum and disconnecting said mandrel therefrom so that said container adheres to said die and the uncut portion of said ribbon adheres to said sleeve, cam means for withdrawing said mandrel from said die and back into said sleeve, means for inserting an article into said open ended container, cam means for moving said die and inserting means relative to one another so that said article is inserted in said container, means for closing the open end of said container, cam means for moving said die and closing means relative to one another so that the open end of said container is closed and cam means connecting said die to a source of air under pressure for ejecting said article and said container from said die.

10. An apparatus for wrapping articles comprising an open ended forming die, means for forming a tubular wrapping member, said means for forming a tubular wrapping member feeding said tubular wrapping member into said die and cooperating therewith to form said member into an open ended container therein, means for inserting an article into said open ended container, means for moving said die and inserting means relative to one another so that said article is inserted in said container, rotating means for closing the open end of said container, means for moving said die and rotating means relative to one another so that the open end of said container engages said rotating means and is wiped closed thereby and means for ejecting said article and said container from said die.

11. An apparatus for wrapping articles comprising an open ended forming die, means for forming a tubular wrapping member having its longitudinal edges overlapped, means for feeding said tubular wrapping member into said die, said member being formed into an open ended container therein, means for inserting an article into said open ended container, means for moving said die and inserting means relative to one another so that said article is inserted in said container, rotating means for closing the open end of said container, said closing means rotating in a direction opposed to the longitudinal overlapped edges of said container, means for moving said die and rotating means relative to one another so that the open end of said container engages said rotating means and is wiped closed thereby and means for ejecting said article and said container from said die.

12. A machine for making wrappers for articles comprising a frame, an open ended forming die mounted on said frame, a sleeve mounted on said frame adjacent said die, rollers mounted on said frame for continuously feeding a ribbon of wrapping material into said sleeve, means between said rollers and said sleeve for folding said ribbon to conform to the inner surface of said sleeve, a source of vacuum, means for connecting said sleeve to said source of vacuum so that said ribbon adheres to the inner surface of said sleeve, a mandrel mounted on said frame for longitudinal movement relative to said sleeve, means for connecting said mandrel to said source of vacuum and disconnecting said sleeve therefrom so that said ribbon adheres to said mandrel for movement outwardly of said sleeve, means forming part of said mandrel and sleeve cooperating to cut a length of said ribbon for movement with said mandrel, means forming part of said feeding means for drawing the uncut portion of said

ribbon away from the cutting portion of said sleeve, means for moving said mandrel and the cut portion of said ribbon adhering thereto into said die, said mandrel cooperating with said die to form the cut portion of said ribbon into an open ended wrapper, means for connecting 5 said die and said sleeve to said source of vacuum and disconnecting the mandrel therefrom so that said open ended container adheres to said die and the uncut portion of said ribbon adheres to said sleeve and means for withdrawing said mandrel from said die and back into said 10 sleeve.
